UNITED STATES PATENT OFFICE

THOMAS W. GREEN, OF PHILADELPHIA, PENNSYLVANIA, ASSIGNOR TO THOMAS WIL-BRAHAM GREEN ENGINEERING CO., OF PHILADELPHIA, PENNSYLVANIA, A CORPORATION OF PENNSYLVANIA

ROTARY BLOWER

Application filed February 10, 1926. Serial No. 87,294.

My invention relates to rotary blowers or exhausters for positive delivery or withdrawal of air and other fluids.

A further purpose is to continuously seal the ends of a plurality of impeller blades, upon a plurality of revolving double concave rotor elements spaced about the circumference and free from intervening shafts. A further purpose is to provide rotor elements which are mounted upon removable heads carrying the shafts upon which they are rotated.

A further purpose is to provide three-way connection at each end of the casing, combining the ends in supporting and conduit functions.

A further purpose is to provide two-stage compression where desired.

A further purpose is to shield the oil within the inside bearings of the blower from air pressure or air suction at the respective ends by venting the journal to atmosphere.

Further purposes will appear in the specification and in the claims.

Of the different forms of my invention I have elected to show but one main from with minor modifications selecting a form that is inexpensive to manufacture, efficient and practical in operation, and which illustrates particularly well the principles involved.

Figure 1 is a front elevation of a blower embodying my invention.

Figure 2 is the end view of Figure 1.

Figure 3 is a longitudinal section taken upon line 3—3 of Figure 2 or 3—3 of Figure 4.

Figure 4 is a transverse section, taken upon line 4—4 of Figure 1 or line 4—4 of Figure 3.

Figure 5 is a longitudinal section taken upon the line 5—5 of Figure 4.

Figure 6 is a vertical section upon the line 6—6 of Figure 5.

Figure 7 is vertical section corresponding generally to Figure 4, but with the rotating parts in a different position from that of Figure 4.

Figure 8 is a perspective view of the central impeller.

Figure 8^a is a perspective view of a portion of the structure of Figure 8.

Figure 8^b is a perspective view showing the

other end of the central impeller from that shown in Figure 8.

Figure 9 is a perspective view of either of the rotor valve units with end plates removed.

Figure 10 is a horizontal central section 55 of a two-stage blower.

Figure 11 is a vertical section taken upon the line 11—11 of Figure 10.

Like numerals refer to like parts in all figures.

Describing in illustration and not in limitation and referring to the drawings:—

The blower casing 15 comprises a main central portion 16 cylindrical at 17 and 18 respectively above and below a central impeller 19, lateral cylindrical portions 20 and 21 casing the rotor valves 22 and 23 and end portions 24 and 25 supporting the whole structure and carrying bearings for the shafts of the rotor elements which include the central impeller 19 and the double concave valve elements 22 and 23.

The impeller 19 is hollow to form radial inlet and radial outlet conduits, two of each having walls that are relatively symmetrical with respect to the impeller axis, and the inlet and outlet conduits when the impeller rotates in one direction become respectively outlet and inlet conduits if the direction of rotation is reversed.

For the purpose of description the direction of the rotor elements is assumed to be that indicated by the arrows in Figure 4, making the inlet conduits at 26 and 27 and the outlet conduits at 28 and 29.

The hub 30 of the impeller is fastened to the main driving shaft 31 as by key 32 (Figure 5) and longitudinal radial walls 33, 34, 35 and 36 from the hub divide the space around the shaft into four equal portions that are encased by outer walls 37 and 38 that make sealing fit with the rotor valve elements.

The impeller, considered as a whole, comprises walls that are not only symmetrical with respect to the axis of the impeller shaft, but are also symmetrical with respect to each of two relatively perpendicular planes that intersect along the axis of the impeller shaft, and lie respectively longitudinally along the middle of the impeller blades 33 and 34 and 100

the middle of the longitudinal walls 35 and 36.

The double concave valve elements 22 and 23 are mounted at horizontally opposite sides of the casing. These valve elements are rigidly carried upon end plates 39 and 40 and 5 41 and 42 respectively which have shaft extensions 43, 44, 45 and 46 which rotate in suitable bearings 47, 48, 49 and 50 driven by gearing from the shaft 31 carrying the central impeller.

The separate heads facilitate manufacture by permitting free machining clear to the edges and allowing a choice of planing or turning for the surfaces affected when the 15 rotor is made from cast metal and permitting free use of sheet metal if desired. At the same time the freedom from intermediate shafting provided by this construction makes the parts much more compact giving a larger internal lune sealing the diameter 20 for the metal involved and shortening the over all width of the case as seen for example, in Figure 11.

The rotor valves 22 and 23 make the same 25 number of revolutions as and synchronize with the impeller 19 and the concave lune-like curves 51, 52, 53 and 54 are formed to make contact seal against the outer ends of the central radial blades 33 and 34, the curves 30 being those generated by the edges of the revolving blades 33 and 34 upon the synchronously revolving cylinders 22 and 23.

Referring to Figure 4 the concave curves 35 51 and 52 are formed to make contact seal with the outer end of the central impeller blade 33 and the opposite curves 53 and 54 of the respective rotor valves make corresponding contact seal against the outer end of the blade 34.

The cylindrical portions 55 and 56 of the 40 diametral impeller and 57, 58, 59 and 60 of the cooperating rotor valves have outside diameters that are preferably though not necessarily the same, (shown the same in the figures).

The cylindrical portion of the impeller makes rolling seal with the cylindrical portions of the rotor valves, the cylindrical portion 55 of the central impeller sealing with the 50 portion 57 of the rotor valve 22 and with the cylindrical portion 59 of the rotor valve 23 while in the same way the opposite cylindrical portion 56 of the central impeller seals respectively against arcuate 55 portions 58 and 60 of the valve elements.

Cutting away the opposite portions of the 60 rotor elements to provide contact seal against the respective ends of the central impeller blade makes it necessary to extend the wall of each conduit section at 61, 62, 63 and 64 respectively to seal against the ends or toes of the concave portions.

These extensions or wings are curved in such way that the toe of the concave portion 65 makes contact seal against their outside until

the circumferences engage after which there is a rolling seal.

The impeller and the rotor elements are symmetrical with respect to their own axes and the axes of the rotor elements are at equal distance from the axis of the impeller so that the rotor elements are similar and symmetrical with respect to their axes. For this reason the extended portion or wing sealing against the toe of one of the rotor elements will also make contact seal against the corresponding toe of the other rotor element.

Assuming the direction of rotation that indicated by the arrows in Figure 4 the end 33 of the impeller seals upon the concave portions 51 and 52 of the opposite rotor elements; the outside of the wing or curved extension 61 makes sliding seal against the toe 65 of the left-hand rotor-valve (Figure 4) and subsequently against the toe 66 of the right-hand rotor valve element and in the same way the wing portion 62 seals against the toe 67 of one rotor and the toe 68 of the other, the wing 63 against the toes 69 and 70 of the respective rotors and the wing 64 against the toes 71 and 72.

Always the fluid through the machine travels radially inward to ultimate outlet along the advancing side of the impeller as at 73 and 74 respectively and the incoming fluid 95 comes in along the receding sections of the central impeller at 75 and 76 respectively. This flow is continuous through the whole revolution of the impeller.

As best seen in Figures 4 and 7 the volume 100 sealed ahead of each advancing impeller, from the position shown in Figure 4 through that of Figure 7 to a position 180° from that of Figure 4, continuously reduces, there being a seal at the left-hand end first from the position of Figure 4 by reason of engagement of the toe 65 along the wing extension 61 of the impeller and then by rolling engagement between the cylindrical portions 57 and 55 respectively of the rotor valve element 22 and 105 impeller 19 and then of the toe 72 with the curve extension 64 at the other end of the impeller.

All this time the volume in the casing of the impeller ahead of the advancing blade 34 115 is diminishing and the air or other fluid included within this space is forced to escape through the passage 28 to outlet 77 at the end of the impeller.

Simultaneously with decreasing volume 120 ahead of the impeller blade 34 there is a corresponding increasing volume to the rear of the impeller 34 in the space from the rear side 75 of the advancing impeller 34 to a continuous seal between the rotor element 23 and the bottom wall 38 of the central impeller.

This seal is between the toe 69 of the right-hand rotor valve element along the curved wing portion 63, then between the circumferential portions 60 and 56 of the rotor valve 130

and impeller and then between the toe 68 and the extended portion 62 at the other end of the impeller until the position 180° from that of Figure 4 is reached.

5 As the volume back of the advancing blade has been increasing the air or other fluid has been continuously drawn into the space back of the advancing blade through the conduit portion 29 which is connected at 78 with the 10 inlet end of the blower.

The opposite end of the impeller works exactly in the same way, the advancing portion 74 continually diminishing the volume within the casing ahead of the impeller 33 and increasing it to the rear of this impeller from a maximum just after the impeller is horizontal to a minimum when it is again horizontal, there being a change from a semi-cylindrical volume above the horizontal space to 20 one below it and vice versa at the horizontal position.

The preferred form of the central impeller 19 is shown in perspective in Figures 8, 8^a and 8^b. The shell cylindrical at 55 and 56 25 respectively, and having extended wings at 61, 62, 63 and 64 is mounted upon a suitable hub 30 and this hub is connected or otherwise fastened to the central driving shaft 31.

Opposite conduit sections as 26 and 27 open 30 at the same end into one of the end chambers 24 or 25 and the opposite corresponding ends of the other conduit sections open into the other end chamber as 24, because the advancing portions of the impeller blade are 35 diametrically opposite to one another and likewise the receding portions of the blade are upon opposite sides of the shaft and these opposite openings at the same end are either outlet or inlet according to the direction of 40 motion of the impeller.

Each of the conduit sections is open at one end into one of the end compartments 24 or 25 and closed at the other end, and adjacent sections are open at different ends and alternate sections at the same end.

45 One of the rotor valve elements is shown in perspective in Figure 9 without its end plates, which may be fastened to the valve element in any suitable way, as by screws or bolts at 50 holes 79.

The rotor valve element in its preferred form is symmetrical not only with respect to its own axis but with respect to each of two relatively perpendicular planes that intersect 55 along the valve axis.

The particular gearing between the shaft of the impeller and the blades of the rotor valve elements is subject to modification according to circumstance and whim of the 60 purchaser or user.

In Figure 6 I show a spur gear 80 keyed to the driving shaft 31 meshing with spurs 81 and 82 upon the respective shafts of the rotor valve elements.

65 There is some tendency for air pressure

or air suction to act disadvantageously upon oil within bearings of the rotor elements and to avoid this I preferably provide air ports 85 (Figure 10) between the bearings and the suction or pressure chambers of the blower. 70

These ports may extend into the shaft and result in equalizing the pressure upon opposite sides of the bearings so that there is no tendency for air leakage through the bearings which, inwardly (as by reason of suction 75 within the blower adjacent the bearing) or outwardly (as by reason of pressure within the blower adjacent the bearing), would tend to carry with it oil of the bearing.

The end sections 24 and 25 of the blower so support the blower and its bearings and also form an air chamber at each end with a three-way connection for air supply or air delivery, chamber outlets 86 and 87 at the side and 88 at the bottom. Two of these outlets are normally closed, that one being used to make pipe connection that will best adapt the blower to the piping. 85

Normally at the inlet of the blower there will be no piping, while at the outlet or delivery end the piping is connected to that one of the three outlets which is most convenient. 90

In Figure 2 I show the air chambers 24 and 25 extending substantially the full width of the blower. 95

My blower is well adapted to two-stage compression and I illustrate this in Figures 10 and 11. In these figures the central impellers 19^a and 19^b of the first and second stages are relatively integral, being carried upon the 100 same hub 30.

The inlet 77^a of the second stage is the outlet 78^a from the first stage.

The impellers and rotor valve elements at opposite ends are substantially identical with that of the form already described. A dividing web 89 separates the opposite sides of the rotor valve elements from one another and a corresponding groove 90, having a bottom concentric with the axis of the central impeller 110 and an outer circumferential portion sealing against the outside circumference of the rotor valve element, separates the first and second stage portions of the central impeller. 115

The cylindrical casing 17, the impeller and valve portion can each be cast in one piece or fabricated from pressed metal portions, thus reducing the tool work and also the weight.

In view of my invention and disclosure variations and modifications to meet individual whim or particular need will doubtless become evident to others skilled in the art to obtain part or all of the benefits of my invention without copying the specific structure shown, and I, therefore, claim all such in so 120 far as they fall within the reasonable spirit and scope of my invention.

Having thus described my invention what I claim as new and desire to secure by Letters Patent is:—

1. A two-stage blower comprising coaxial casings, coaxial double impeller blades in the two casings, a shaft carrying both of the double impeller blades, arced sealing walls on opposite sides of the shaft spaced from each of the impeller blades, webs dividing the spaces inside of the arced walls into quadrants having inlet and outlet openings alternating at opposite ends, sealing wings at the ends of the arced walls, the outlets of the impeller in one casing connecting with the inlets to the impeller in the other casing, wings at the edges of the arced walls and lunar arced rotor seals diametrically opposite in each of the two compartments sealing along their lunar surfaces with the ends of the impellers and along intervening arced surfaces with the arced walls of the impellers.
2. An impeller casing, a shaft therein, an impeller blade on the shaft comprising two pairs of oppositely facing blades, oppositely extending one pair from the other parallel with the shaft, impeller end walls perpendicular to the shaft providing inlets and outlets upon opposite sides of the blades, intermediate walls dividing the pairs into two parts perpendicular to the shaft and providing outlets from one compartment thus formed as inlets to the other and diagonally opposite placed lunar seals for the blades having double lunar concave surfaces, intermediate convex surfaces and end walls, intermediate walls cooperating with the blades to seal them and seal with the compartment division of them and driving means for the blades and seals timing them to register with each other.
